TAB FOR HOLDING THREAD ON A BOBBIN

Haruo Ueda, 36 Sakurazono-machi; Masano Sugi, 607-4
Midorigaoka-cho; and Hiroshi Chayamichi, 3-1 Nakagawa-machi, 2-chome, all of Nobeoka, Japan

Original design application June 23, 1970, Ser. No. 23,636,
now abandoned. Divided and this application Oct. 12,
1971, Ser. No. 188,647

Claims priority, application Japan Dec. 23, 1969

Term of patent 14 years

Int. Cl. D5—99

U.S. Cl. D3—19 A

FIG. 1

FIG. 2

FIG. 3

FIG. 1 is a perspective view of a tab for holding thread on a bobbin showing our new design, the other side being a mirror image thereof;

FIG. 2 is a perspective view of a second embodiment of the design of FIG. 1; and

FIG. 3 is a perspective view of a third embodiment thereof.

This is a division of application Ser. No. D. 23,636 filed June 23, 1970 and now abandoned.

We claim:

The ornamental design for a tab for holding thread on a bobbin, as shown and described.
